SELF-RETRACTING HOOK MECHANISM

Charles J. Benson, 220 Worrell Drive, Springfield, Pa.; Edwin F. Potter, Jr., 73 Lake Ave., R.F.D. 1, St. James, N.Y.; Carl Rose, 545 Shoemaker Road, Elkins Park, Pa.; and Elwood P. Schollenberger, 17 N. Norwinden Drive, Springfield, Pa.

Original application June 30, 1952, Ser. No. 296,513, now Patent No. 2,830,841, dated Apr. 15, 1958. Divided and this application Mar. 5, 1958, Ser. No. 719,457

1 Claim. (Cl. 294—83)

(Granted under Title 35, U.S. Code (1952), sec. 266)

The invention described herein may be manufactured and used by or for the Government of the United States of America for governmental purposes without the payment of any royalties thereon or therefor.

This invention relates to new and useful improvements in a releasing device, and more particularly to improvements in self-retracting hook mechanism. After an object has been ejected from a forward hook mechanism mounted on supporting structure such as an airplane, the attaching mechanism of the invention is automatically retracted within the supporting structure so that the external surface of said supporting structure becomes free of any of the attaching members. This is a division of my Patent No. 2,830,841 issued April 15, 1958 for Self-Retracting Hook Mechanism. The present invention is designed to be used in conjunction with a hook mechanism of the type that retains the shackle, thereby preventing the stores from moving out of either hook.

Previously, external stores such as bombs, gas tanks, rescue equipment, jato (jet-assist-take-off) bottles, etc., were attached to airplanes by means of fixed hook structures or retractable hooks that were articulated. The fixed hooks did not retract to form a flush surface with the airplane when their intended purpose had been fulfilled. These projections were not objectionable when the aircraft travelled at relatively slow speed. However, with the advent of high-speed aircraft, airflow becomes critical, and any projection that interferes with the smooth flow of air over the surface of an object such as an airfoil passing through the air causes an additional drag that reduces the aerodynamic efficiency. The retractable hooks that are articulated are not flexible enough to permit installation of present external stores having variable distances between suspension lugs. Moreover, the articulated hooks require actuation linkage ties to the forward hook, and as such are not adaptable to variable suspension lug systems.

With this in mind, the principal object of this invention is to provide a rear hook releasing device that retracts within or flush with its supporting surface so that all projecting arms of said device are withdrawn within or flush with its supporting area immediately after the attached object is released and ejected from its forward fastening and said device.

Another object is to provide a mechanism that will automatically retract the hook by the act of sliding an object out of the hook throat.

A further object of the invention is to provide a hook that will assume a retracted position flush with the aerodynamic contour of the airplane.

A still further object of the invention is to provide a mechanism that will remain in extended position when attaching a load.

A still further object of the invention is to provide a device that is compact and small in size to enable easy installation and removal for maintenance purposes, and

2

permitting installation where very little space is available.

These and other objects of the invention and the various features and details of construction and operation thereof are hereinafter more fully set forth and described with reference to the accompanying drawings, in which like numbers refer to like parts.

Fig. 1 is a side-elevational view of an embodiment of the invention, the mechanism being in the retracted position.

Fig. 2 is a side-elevational view of the mechanism of Fig. 1, showing the action between the crescent-shaped latch and cam plate as the hook is rotated into extended position.

Fig. 3 is a side-elevational view of the same mechanism with the load-supporting means in extended position prior to locking.

Fig. 4 is a side-elevational view of the mechanism with the load-supporting means in the locked extended position prior to loading.

Fig. 5 is a side-elevational view of the mechanism in the extended position with a load attached.

Fig. 6 is a side-elevational view of the mechanism after release of the load.

Fig. 7 is a sectional view of the mechanism taken along line 7—7 of Fig. 3, with the load-supporting means in extended position prior to locking.

Fig. 8 is a perspective view of the mechanism assembly. Figs. 9a, 9b and 9c form an exploded view of the load-supporting means, working lever and crescent-shaped latch elements.

Similar numerals refer to similar parts throughout the several views.

The self-retracting mechanism will best be understood by referring to Figs. 1 through Fig. 9c inclusive. This device consists of four major elements mounted on a frame assembly, namely, a load supporting means or hook 87 rotatable on a shaft 89, a crescent-shaped latch 91 rotatable on a pin 93 of said load-supporting means, a lever 95 rotatable on said shaft, and a cam plate 85 having joining arcuate cam surfaces 109 and 111. Two springs 97 are connected at one end to a pin 99 of said latch and anchored at the other end to a pin 101 mounted on said frame assembly. Said frame assembly is composed of a center cam plate 85 between two spacer plates 83, all riveted between two side plates 81. A thin metal case or housing, not shown, is designed to retain said mechanism. (See Figs. 8, 9a, 9b and 9c.)

In Fig. 1, the mechanism is shown in the retracted position. Said load-supporting means is retained in the retracted position by the action latch 91 mounted on pin 93 of the load-supporting means. Said mechanism can be extended by pressing a screw-driver inward against one end of said lever 95. This act extends said lever an amount sufficient to be grasped and rotated counterclockwise about said shaft 89. (See Fig. 2.) Said rotation causes said lever to bear against the toe 105 of said latch and rotate both latch and load-supporting means counterclockwise. As the latch is rotated, the cam surface 115 of said latch cams against the cam surface 111 of said cam plate until the lever is rotated to the position shown in Fig. 4.

Continued rotation of said lever forces said latch to be rotated to a position where its camming surface 171 cams against camming surface 109 of said cam plate. At the same time, the toe 105 of said latch engages a heel notch 107 of said lever, thereby locking said load-supporting means in the "ready" position. (See Fig. 4.) (It can be seen that rotation of said load-supporting means to extended position is limited by said spacer plates 83.)

The mechanism is loaded by inserting the rear lug of the store in the throat of said load-supporting means.

Said lug bears against the tip 103 of the latch 91 and forces both said latch and lever to rotate, the former in a counterclockwise direction and the latter in a clockwise direction. This action disengages toe 105 from heel notch 107. The cam surface 117 cams against cam surface 109. (See Fig. 5.) Said mechanism will remain in the extended position as long as said lug store is in the throat of said load-supporting means.

As the forward hook mechanism releases the store and the store moves aft, either under the action of air loads or positive ejection by the forward hook, said lug moves out of the throat of said load-supporting means, enabling springs 97 to pull said latch away from the cam surface 109 of cam plate 85 to the position indicated in Fig. 6. Continued rotation of said latch due to the influence of said springs causes the load-supporting means to rotate into retracted position flush with the contour of the airplane. A spacer block 113 mounted on the throat end of said load-supporting means limits the rotation of the lever in the retracted position.

From the foregoing description and illustration of the present invention it is apparent that a self-releasing mechanism of simple design is provided. The rear lug or shackle of a load can be installed quickly and easily, and, when positive ejection of the load is accomplished by a forward ejecting device, said mechanism will automatically retract to a position flush with the contour of the airplane.

The invention is not to be construed as limited to the particular rear location described herein, since this is regarded to be illustrative rather than restrictive. For example, the device can be located forward of the ejecting type hook mechanism, said relative location being

determined by the suspension system to be used, or installed to suit any suspension lug configuration desired.

We claim:

- 5 A self-retracting device comprising a frame assembly including a pin, a cam plate having joining arcuate cam surfaces with their centers in spaced relation, a shaft substantially concentric with one of said centers and spaced from the other center, load-supporting means mounted on said shaft, said load-supporting means including a hook rotatable into extended and retracted positions, a crescent-shaped latch having a toe and tip pivotally mounted on said load-supporting means for rotation into holding position with said toe locking against one of said cam surfaces and into releasing position with 10 the crescent convex surface slidably engaging the other cam surface, said crescent latch having its tip end adapted to be extended into the hook and having a pin projecting therefrom, a lever rotatably mounted on said shaft and having a notch engageable by said toe of the crescent-shaped latch in holding position, a spring attached to said 15 pin of said crescent latch and to said pin of said frame assembly, said spring urging said crescent latch, said load-supporting means and said lever into retracted position, and mating cam surfaces on said crescent-shaped latch and said lever for cooperation in the transition 20 from retracted position to extended position.
